Filed Apr. 12, 1963, Ser. No. 74,413

Term of patent 14 years

(Cl. D52—6)

FIGURE 1 is a perspective view of a portable housing unit for cryotherapy or the like equipment showing our new design as seen from the left front of the unit;

FIGURE 2 is a left side view of the unit of FIGURE 1;

FIGURE 3 is a perspective view of the upper portion of the unit of FIGURE 1 as seen from the right rear of the unit; and

FIGURE 4 is a cross sectional view of the base of the unit taken substantially along line 4—4 of FIGURE 2.

The essential features of our disclosed design reside in the portions shown in full lines in the drawing.

We claim:

The ornamental design for a portable housing unit for cryotherapy or the like equipment, substantially as shown and described.
